CONE JACKET APPLYING MACHINE

James Balton, Baltimore, Md., assignor to Maryland Baking Company, Inc., Baltimore, Md., a corporation of Maryland

Application May 23, 1940, Serial No. 336,840

30 Claims. (Cl. 226—2)

My invention comprises a new and improved machine for applying pre-formed jackets to ice cream cones.

The jackets, which this machine is designed to apply, constitute the subject matter of my application, Ser. No. 322,853, filed March 7, 1940, and comprise hollow frusto-conical bodies of paper or other suitable material, of a size and form constructed to fit the cones between the bowl (or the nesting ring) of the cone and a stop ring (or lugs) located adjacent the point of the cone.

Primarily, the present invention has for its object to provide means for assembling cones and jackets on a commercial scale by a machine which is simple in construction, inexpensive to maintain, and by means of which the jackets are fed from a magazine into carriages or holders, the holders brought to a loading station where the cones are placed in the jackets, then the jackets are brought to their final positions and "locked" to the cones automatically, after which the jacketed cones are discharged from the machine into a suitable receptacle.

In general, the invention has for an object to provide an endless conveyor for the carriages or cone-jacket carriers, a mechanism for depositing the jackets, one at a time, from a stack of nested jackets into each "pocket" of the carriage, a mechanism for pressing the cones and jackets together to "lock" the jackets to the cones, and a discharge mechanism for delivering the jacketed cones from the carriages.

Other objects will in part be obvious and in part be pointed out hereinafter.

To the attainment of the aforesaid objects and ends the invention still further resides in the novel details of construction, combination and arrangement of parts, all of which will be first fully described in the following detailed description, and then be particularly pointed out in the appended claims, reference being had to the accompanying drawings, in which:

Fig. 1 is an elevation of the machine viewed from the front.

Fig. 2 is a side elevation of the machine looking from right to left, in Fig. 1.

Fig. 3 is a side elevation of the machine, looking from left to right, in Fig. 1.

Fig. 4 is a vertical section on the line 4—4 of Fig. 1.

Fig. 5 is an enlarged detail vertical section on the line 5—5 of Fig. 1.

Fig. 6 is an enlarged detail top plan view of one of the jacket carriers or carriages.

Fig. 7 is an inverted plan view of the parts shown in Fig. 6.

Fig. 8 is a cross section on the line 8—8 of Fig. 6.

Fig. 9 is a cross section on the line 9—9 of Fig. 6, with the carrier partly open for discharge of the jacketed cones.

Fig. 10 is a detail perspective view of one of the jacket feeding elements.

10 In the drawings, in which like numbers and letters of reference indicate like parts in all the figures, *c* designates the cones, *n*, *r*, the nesting rings, *r* the stop ring (lugs or projections), *J* the jackets, *A* the station where the jackets are fed to the carriers, *B* the station where the cones are placed in the jackets carried by the carriers, *C* the station where the cones are pressed into the jackets so that the lower ends of the jackets pass the stop ring *r*, and *D* the station where the jacketed cones are freed from the carriers and discharged from the machine.

The machine comprises a frame composed of uprights 1, top and bottom side braces 2, 2^a, back and front braces 3, 4 and 5, and intermediate side braces 6.

25 Bars 7 and 8 (the latter being adjustably secured as at 9, 10) are secured to the uprights 1 and have bearings for the conveyor shafts 11 and 12, respectively (see Fig. 2).

30 On each shaft 11 and 12 is mounted in spaced relation two sprockets 13 around which endless chains 14 pass. These chains, at suitable intervals, have links provided with arms 15 having bearings for the trunnions 16 of the carriers or 35 carriages.

The construction of the carriers is best shown in Figs. 5 to 9, inclusive, by reference to which it will be seen that the trunnions 16 are on side plates 17 between which and mounted at the 40 ends in the side plates are parallel shafts 18 on each of which is secured (by spot welding or any other suitable way) a plate 19.

The two plates 19 have their adjacent edges 45 in proximity and are held in the same plane normally by means of springs 22 and abutment lugs 24 against which the fingers 23 rest (see Fig. 8). Each plate 19 has one-half of an opening to receive jackets; flexible, resilient washers 20 are clamped to the plates 19 by clamp plates 21 and screw bolts and nuts 30, the washers 20 having arcuate portions to correspond with the arcuate openings in the plates.

Secured to the under side of the plates 19 are 50 thin resilient fingers 29 which serve to steady and

guide the jackets and cones and keep them centered in the openings.

The carriers are so weighted that they will swing on their trunnions 16 to maintain a horizontal position, as shown in Figs. 1 to 5, inclusive.

In order to hold the carriers in horizontal position against swinging while at the jacket-loading station A, a fixed guide 26 is provided under the horizontal part of which an end plate 17 passes (see Fig. 5), and in order to hold the carriers against swinging while passing from the cone-loading station B downwardly, fixed vertical guides 25 are provided to contact the sides of the plates 17 (see Figs. 2, 3 and 5). As the carriers pass to the presser station where the jackets are "locked" to the cones, bottom guides 27, over which the plates 19 ride, engage the bars 91 which slide over the horizontal portions of the guides 27 (see Fig. 4). The guides 25 are supported by brackets 28 (see Fig. 1).

At the top of the machine are side bracket plates 31 which support a plate 54 which is the bottom of the jacket magazine 51, there being a door 52 through which the magazine may be loaded. Within the magazine 51 is a set of jacket-stack guides 53, one for each opening in the plate 54, which openings correspond in number and position to the openings in the carriers.

Two flexible elastic washers 55 are secured to plate 54 by clamp plates 56, one washer above and one beneath plate 54 (see Fig. 5).

The bracket plates 31 have arcuate slots 32 for the cap screws 37 which secure the side arms 35 adjustably in position. The arms 35 are pivoted to the plates as at 33 and 36 (Fig. 2) and 33, 34 (Fig. 5), 33 being a cross shaft and 34 a stub shaft.

Two spaced-apart feed shafts 38 are journaled in said side arms 35 and carry gears 41 which mesh with like gears 41 on shafts 33 and 34 (see Fig. 5). On each shaft 38 is secured a set of feed elements or wipers 39 having wings 40, there being one feed element to each stack of jackets. These feed elements are preferably composed of rubber or other suitable resilient and yieldable substance. A single element is shown in Fig. 10.

The shafts 38 are driven from shaft 33 through the gear train 41, shaft 33 being driven at a constant speed by means of sprockets 42 and chain 43 from the first motion shaft 44 which is turned continuously at a uniform speed by any suitable motor (not shown).

The conveyor 14 is driven step-by-step through a Geneva gear system composed of the elements 45 to 49 inclusive (see Figs. 1 and 3).

The shaft 44 also carries a cam 50 that is engaged by a roller 83 on an arm 82 fast to a shaft 80 to which shaft the arms 84 that carry the discharge chute 85 are also fastened. The chute 85 is held normally out of the way of the carriers by spring 87, which spring also serves to maintain contact between roller 83 and cam 50.

In order to guide the jackets into the openings of the carriers at the jacket-loading station A as they are fed from the stacks by the wiper wings 40, pins 58 are provided. These pins are mounted on a plate 57 that is secured to a vertical bar 59 (see Fig. 4), that is part of a vertically movable frame composed of the bar 59, the vertical bar 60, cross bars 61, and roller-carrying arm 62. The frame is held down by a light spring 86 which also serves to maintain contact between the roller on arm 62 and the cam 63 which it contacts.

The cam 63 is mounted on a shaft 64 journaled in suitable bearings on the rear uprights 1 and carrying a pinion 65 which meshes with a rack 68 on a rack-carrying frame 69.

5 The shaft 64 also carries side arms 66 whose rounded ends 67 serve to engage the tops of the plates 19 to open the carriers (see dotted lines, Fig. 9) for the purpose of releasing the jacketed cones into the chutes, as will later more clearly appear.

On one side of the machine is a vertically reciprocable bar 71 mounted to slide in bearings 72 secured to the side braces 6. Bars 70 are secured to the bar 71 and extend inwardly and carry the frame 69 which is rigidly mounted on the bars 70 to move up and down with bar 71.

73 is a bracket also rigidly secured to bar 71 and to which bracket vertical bars 74 are fastened and straddle the shaft 11. At their lower ends the bars 74 carry a plate 76 on which is mounted a spring-loaded pusher or presser plate 75, the plate 76 being braced by diagonal bars 77 (see Figs. 1 and 4).

The bar 71 at its lower end has an arm 79 which carries a roller 78 to ride in the fork of an arm 81 that is attached to the shaft 80, whereby, as shaft 80 rocks, bar 71 is reciprocated (see Fig. 2).

At the discharge station D another fixed guide 88 is provided to contact a side plate 17 of the carriers, and hold the carriers from swinging while the ends 67 of arms 66 are opening the carriers (see Figs. 4 and 9).

At the discharge station D another fixed guide 88 is provided to contact a side plate 17 of the carriers and hold the carriers from swinging while the ends 67 of arms 66 are opening the carriers (see Figs. 4 and 9).

89 designates a cross car which supports a guide 90, through a slot in which the bar 59 passes.

Operation

Assume the parts to be positioned as in Figs. 1 to 5 inclusive, and power is being applied to shaft 44 to effect its continuous rotation. One rotation of shaft 44 gives a one-quarter turn to shaft 11 via the Geneva gearing. Shaft 33, however, is continually turned via sprockets 42 and chains 43, in timed relation to the conveyor steps.

As roller 48 enters a slot in Geneva gear 45 and moves through about 90°, conveyor 14 is given one step which brings an empty carrier in position at station A. During this quarter movement wiper-wings 40 are also turned 90° from the position shown in Fig. 5.

During the next approximately 180° turn of shaft 44 cam 50 comes into position to depress roller 83 and rock arms 82, 81 and 84 to bring chute 85 beneath the carrier at station D and to lower bar 71 and with it frame 69 and rack 68, thereby projecting pins 58 upwardly through the jacket-receiving openings in the carrier station A, by reason of cams 63 lifting 62 and also swinging arms 66 counter-clockwise in Fig. 4 to lower the ends 67 to plates 19 of the carrier at station D and press the same down (Fig. 9) to release previously jacketed cones into chute 85. During this 180° movement of shaft 44 wiper wings 40 strip off the lowermost jackets of the stack and deliver the same over the pins 58 into the openings of the carrier at station A.

As pins 58 are raised, pusher 77 is lowered to push the cones into the jackets in the carrier at station C until the lower ends of the jackets are

passed by the stop rings or lugs τ and the jacket thus secured to the cone.

Further movement of shaft 44 to complete its turn, causes pins 58 to be lowered clear of the jackets, pusher 16, 17 to be raised clear of the cones in the lowest carriage, arms 66 to be swung back up, and chute 85 swung out again, thus completing one cycle of operation.

During this cycle, while the conveyor is stationary, an attendant drops cones into the jackets held in the carrier which is located at station B. If the machine is so speeded up that there is insufficient time to fill all jackets at station B, the remainder may be filled during the lowering of the carriage from station B.

From the foregoing description, taken in connection with the accompanying drawings, it is thought that the construction, operation and advantages of my invention will be clear to those skilled in the art and, while I have shown a preferred form of the invention, I wish it understood that I am not to be limited thereto, since modifications and changes in the details of construction can readily be made by those skilled in the art within the scope of the appended claims.

What I claim is:

1. In a machine of the character described, a magazine for open or uncollapsed cone-jackets, a conveyor, a carrier mounted on and conveyed by said conveyor past said magazine, means for dispensing jackets from said magazine into said carrier as it comes into position with respect to said magazine, said carrier having provision to hold said jackets to receive cones, means to push said cones into said jackets to "lock" the jackets to the same, and means to discharge the jacketed cones from the machine.

2. A machine for applying jackets to cones, comprising a jacket magazine, at least one jacket carrier, means to feed open or uncollapsed jackets from the magazine into the carrier for the reception of cones, and means for effecting the assembly of the jackets or cones while in the carrier to secure the jackets to the cones.

3. A machine for applying jackets to cones, comprising a jacket magazine, at least one jacket carrier, means to feed open or uncollapsed jackets from the magazine into the carrier for the reception of cones, means for assembling the jackets while in the carrier with the cones, and means to release the jacketed cones from the carrier and deliver same from the machine.

4. In a machine of the character described, in combination, a support for a nested stack of jackets, a carrier for jackets and cones, means for removing a jacket from the stack and placing it in the carrier for the reception of a cone, and means to effect the fitting of the wrapper to the cone while in the carrier.

5. In a machine of the character described, in combination, a support for a nested stack of jackets, a carrier for jackets and cones, means for removing a jacket from the stack and placing it in the carrier for the reception of a cone, means to effect the fitting of the wrapper to the cone while in the carrier, and means to discharge the jacketed cone from the carrier.

6. In a cone jacketing machine, a carrier comprising side plates, connecting rods between said side plates, a pair of transversely disposed plates pivotally mounted between said side plates and provided with at least one jacket-receiving hole between them, and means continuously acting to maintain said pair of plates in the same plane.

7. In a cone jacketing machine, a carrier comprising side plates, connecting rods between said side plates, a pair of transversely disposed plates pivotally mounted between said side plates and provided with at least one jacket-receiving hole between them, means continuously acting to maintain said pair of plates in the same plane, and flexible sheets secured to said pair of plates and having a hole between them corresponding in location to the hole in said pair of plates.

8. In a cone jacketing machine, a carrier comprising side plates, connecting rods between said side plates, a pair of transversely disposed plates pivotally mounted between said side plates and provided with at least one jacket-receiving hole between them, means continuously acting to maintain said pair of plates in the same plane, flexible sheets secured to said pair of plates and having a hole between them corresponding in location to the hole in said pair of plates, and flexible resilient jacket steadyng fingers secured to said pair of plates in cooperative relation to said holes.

9. In a machine for jacketing cones, a supporting frame, an endless conveyor mounted in said frame, at least one carrier on said conveyor, said machine having a jacket loading station, a cone loading station, a cone and jacket assembling station, and a jacketed-cone discharging station, means at the jacket loading station for placing a jacket in the carrier, means at the cone and jacket assembling station for effecting the securing of the jacket to the cone, and means at the discharging station for releasing the jacketed cone from the carrier.

10. In a machine for jacketing cones, a supporting frame, an endless conveyor mounted in said frame, at least one carrier on said conveyor, said machine having a jacket loading station, a cone loading station, a cone and jacket assembling station, and a jacketed-cone discharging station, means at the jacket loading station for placing a jacket in the carrier, means at the cone and jacket assembling station for effecting the securing of the jacket to the cone, and means at the discharging station for releasing the jacketed cone from the carrier, said carrier having an opening in which the jacket rests.

11. In a machine for jacketing cones, a supporting frame, an endless conveyor mounted in said frame, at least one carrier on said conveyor, said machine having a jacket loading station, a cone loading station, a cone and jacket assembling station, and a jacketed-cone discharging station, means at the jacket loading station for placing a jacket in the carrier, means at the cone and jacket assembling station for effecting the securing of the jacket to the cone, and means at the discharging station for releasing the jacketed cone from the carrier, said carrier having an opening in which the jacket rests, said releasing means comprising mechanism for spreading said opening to permit the jacketed cones to pass through.

12. In a machine for jacketing cones, a supporting frame, an endless conveyor mounted in said frame, at least one carrier on said conveyor, said machine having a jacket loading station, a cone loading station, a cone and jacket assembling station, and a jacketed-cone discharging station, means at the jacket loading station for placing a jacket in the carrier, means at the cone and jacket assembling station for effecting the securing of the jacket to the cone, and means at the discharging station for releasing the jacketed cone from the carrier.

cone from the carrier, said jacket loading means comprising a holder for a nested stack of jackets and means for removing a jacket at a time from the stack and delivering it to the carrier.

13. In a machine for jacketing cones, a supporting frame, an endless conveyor mounted in said frame, at least one carrier on said conveyor, said machine having a jacket loading station, a cone loading station, a cone and jacket assembling station, and a jacketed-cone discharging station, means at the jacket loading station for placing a jacket in the carrier, means at the cone and jacket assembling station for effecting the securing of the jacket to the cone, and means at the discharging station for releasing the jacketed cone from the carrier, said jacket loading means comprising a holder for a nested stack of jackets and means for removing a jacket at a time from the stack and delivering it to the carrier, said jacket removing and delivering means including means to hold back all but the outermost jacket of the stack, and means for engaging said outermost jacket and pulling it loose from the stack.

14. In a machine for jacketing cones, a supporting frame, an endless conveyor mounted in said frame, at least one carrier on said conveyor, said machine having a jacket loading station, a cone loading station, a cone and jacket assembling station, and a jacketed-cone discharging station, means at the jacket loading station for placing a jacket in the carrier, means at the cone and jacket assembling station for effecting the securing of the jacket to the cone, and means at the discharging station for releasing the jacketed cone from the carrier, said jacket loading means comprising a holder for a nested stack of jackets and means for removing a jacket at a time from the stack and delivering it to the carrier, said jacket removing and delivering means including a resilient device through which the jackets are pulled from the stack and by which succeeding jackets are held back, and means to grasp the first jacket and pull it from the stack.

15. In a machine for jacketing cones, a supporting frame, an endless conveyor mounted in said frame, at least one carrier on said conveyor, said machine having a jacket loading station, a cone loading station, a cone and jacket assembling station, and a jacketed-cone discharging station, means at the jacket loading station for placing a jacket in the carrier, means at the cone and jacket assembling station for effecting the securing of the jacket to the cone, means at the discharging station for releasing the jacketed cone from the carrier, said jacket loading means comprising a holder for a nested stack of jackets and means for removing a jacket at a time from the stack and delivering it to the carrier, and jacket guiding means for guiding the jacket released from the stack into the carrier.

16. In a machine for jacketing cones, a supporting frame, an endless conveyor mounted in said frame, at least one carrier on said conveyor, said machine having a jacket loading station, a cone loading station, a cone and jacket assembling station, and a jacketed-cone discharging station, means at the jacket loading station for placing a jacket in the carrier, means at the cone and jacket assembling station for effecting the securing of the jacket to the cone, and means at the discharging station for releasing the jacketed cone from the carrier, said means at the cone and jacket assembly station comprising a device to force the cones into the jackets to effect a "locking" of the jackets to the cones.

17. In a machine for jacketing cones, a supporting frame, an endless conveyor mounted in said frame, at least one carrier on said conveyor, said machine having a jacket loading station, a cone loading station, a cone and jacket assembling station, and a jacketed-cone discharging station, means at the jacket loading station for placing a jacket in the carrier, means at the cone and jacket assembling station for effecting the securing of the jacket to the cone, and means at the discharging station for releasing the jacketed cone from the carrier, said means for releasing the jacketed cones from the carrier including means to open the carrier to permit the jacketed cones to fall out of the carrier.

18. In a machine for jacketing cones, a supporting frame, an endless conveyor mounted in said frame, at least one carrier on said conveyor, said machine having a jacket loading station, a cone loading station, a cone and jacket assembling station, and a jacketed-cone discharging station, means at the jacket loading station for placing a jacket in the carrier, means at the cone and jacket assembling station for effecting the securing of the jacket to the cone, and means at the discharging station for releasing the jacketed cone from the carrier, said means for releasing the jacketed cones from the carrier including means to open the carrier to permit the jacketed cones to fall out of the carrier, and means to catch the falling cones and deliver same from the machine.

19. In a machine of the character described, a carrier comprising a pair of cooperating plates pivotally mounted between side plates, that are in turn mounted on a conveyor, a shaft past which said conveyor carries said carrier, said plates having between them a hole to receive and retain a cone jacket, and means operated by the turning of said shaft while said carrier is adjacent thereto for moving said pair of plates apart to free the jacket through said hole.

20. In a machine of the character described, a carrier comprising a pair of cooperating plates pivotally mounted between side plates, that are in turn mounted on a conveyor, a shaft past which said conveyor carries said carrier, said plates having between them a hole to receive and retain a cone jacket, and means operated by the turning of said shaft while said carrier is adjacent thereto for moving said pair of plates apart to free the jacket through said hole, said means comprising arms on said shaft having ends to engage said pair of plates and swing them on their pivots.

21. In a jacketing machine of the character described, a supporting frame, two spaced shafts, a pair of spaced apart sprockets on each shaft, endless chains taking around said sprockets and providing therewith an endless conveyor, a set of carriers having trunnions and being pendently mounted by said trunnions on said conveyor, the machine having a jacket loading station, a jacket and cone assembly station and a discharge station, means at the jacket loading station for holding a nested stack of jackets, means for separating a jacket from the stack and delivering it to the carrier at the jacket loading station, means at the jacket and cone assembly station for applying the jacket securely to the cone, and means at the discharge station for freeing the jacketed cone from its carrier, the jackets in the carriers being adapted to have cones placed therein while the carriers pass from the jacket loading station to the jacket and cone assembling station.

22. In a jacketing machine of the character described, a supporting frame, two spaced shafts, a pair of spaced apart sprockets on each shaft, endless chains taking around said sprockets and providing therewith an endless conveyor, a set of carriers having trunnions and being pendently mounted by said trunnions on said conveyor, the machine having a jacket loading station, a jacket and cone assembly station and a discharge station, means at the jacket loading station for holding a nested stack of jackets, means for separating a jacket from the stack and delivering it to the carrier at the jacket loading station, means at the jacket and cone assembly station for applying the jacket securely to the cone, means at the discharge station for freeing the jacketed cone from its carrier, the jackets in the carriers being adapted to have cones placed therein while the carriers pass from the jacket loading station to the jacket and cone assembling station, and means cooperating with said carriers to hold them against swinging on their trunnions while at the jacket loading station, the jacket and cone assembling station and the discharge station.

23. In a machine for jacketing cones, a supporting frame, an endless conveyor mounted in said frame, at least one carrier on said conveyor, said machine having a jacket loading station, a cone loading station, a cone and jacket assembling station, and a jacketed-cone discharging station, means at the jacket loading station for placing a jacket in the carrier, means at the cone and jacket assembling station for effecting the securing of the jacket to the cone, means at the discharging station for releasing the jacketed cone from the carrier, means to impart a continuous movement to said jacket placing means at the jacket loading station and a step-by-step movement to said conveyor in timed relation to one another.

24. A machine for applying conical jackets to the stems of ice cream cones, which machine comprises a magazine for nested jackets, an endless conveyor, at least one jacket carrier on said conveyor, means to feed the jackets from the magazine, one at a time, to said carrier for the reception of cones, means for effecting the assembly of the cones and jackets while in the carrier to effect the securing of the jackets to the cones, and means for effecting the removal of the assembled jackets and cones from the carrier.

25. A machine for applying conical jackets to the stems of ice cream cones, which machine comprises a magazine for nested jackets, an endless conveyor, at least one jacket carrier on said conveyor, means to feed the jackets from the magazine, one at a time, to said carrier for the reception of cones, means for effecting the assembly of the cones and jackets while in the carrier to effect the securing of the jackets to the cones, and means for effecting the removal of the assembled jackets and cones from the carrier, the removing means comprising means for opening the carrier so the assemblies will pass through, and means to receive the assemblies and discharge them from the machine.

26. In a machine for jacketing pastry cones, a supporting frame, an endless conveyor mounted in said frame, at least one carrier on said conveyor, said machine having a jacket loading station, a magazine for stacked nested jackets located at the jacket loading station, means for removing a jacket at a time from the stack and delivering it to the carrier, said carrier having an opening to receive a jacket to be held therein by said carrier, means to guide the jacket, on leaving the magazine, into said opening, and means located at another place in the path of travel of the conveyor for spreading the carrier opening to effect discharge of the jacketed cones.

27. In a machine for jacketing cones, a supporting frame, an endless conveyor mounted in said frame, at least one carrier on said conveyor, said machine having a jacket loading station, a magazine for stacked nested jackets located at the jacket loading station, means for removing a jacket at a time from the stack and delivering it to the carrier, said carrier having an opening to receive a jacket to be held therein by said carrier, and means to guide the jacket, on leaving the magazine, into said opening, said guiding means comprising a rod over which the jacket is passed by the jacket removing means.

28. In a machine of the character described, a conveyor having a carrier, a jacket-stack magazine having a bottom with an opening for the stack, means to hold the stack in place with the lowermost jacket in said opening, means below the opening for removing the lowermost jacket from the stack and conveying it to said carrier, while the carrier is located beneath the stack, and means operating through said carrier to guide the jacket fed from the stack into the carrier.

29. In combination with a jacket receiver having an opening to receive and hold a jacket, a magazine case, a vertically disposed tubular guide in the case for a stack of nested jackets, means to hold the stack in place in the magazine case with the lowermost jacket in the stack projected through an opening in the bottom of the case, rotary elements for engaging said lowermost jacket and moving it downwardly to free the same from the stack, and means to guide the jacket, on being detached from the stack, into the opening of the receiver and thereby prevent the jacket from getting out of alignment with the receiver opening while being deposited in the same.

30. In a machine for applying paper jackets to pastry cones, a magazine for nested conical jackets, a jacket conveyor, means for removing jackets one at a time from the magazine and delivering them to the conveyor, means to hold the jackets in the conveyor in vertical position to receive the pastry cones loosely at one location along the path of the conveyor, and means located at another place along said path for forcing the cones and jackets together to secure the jackets to the cones.

65 JAMES BALTON.
